UNITED STATES PATENT OFFICE

FRANCIS R. MEGINNISS, OF ALBANY, NEW YORK

SWITCH

Application filed April 3, 1930. Serial No. 441,365.

My invention relates to electrical switches and particularly to devices of this character adapted for use in places where inflammable or explosive fluids are present.

5 One of the objects of my invention is to provide a circuit making and breaking device which is completely enclosed in a gas proof container so that all danger of igniting inflammable or explosive gases by sparks or 10 arcs when the mechanism is actuated is eliminated. Another object is to provide a means for manually or otherwise operating the switch which will be positive, and at the same time, wholly independent of the sealed 15 switch mechanism. A further object is to provide a hermetically sealed switch and an exposed means for effecting an operation thereof in which there is no direct contact between the switch and its operating means.

20 I accomplish these and other objects, which will be apparent as the description proceeds, by enclosing a circuit making and breaking means and an inertia operated actuating means therefor within a sealed container, and by providing a means exterior 25 of the container for developing potential energy, manually or otherwise, and suddenly releasing and transmitting this energy to the actuating means as kinetic energy to effect 30 an operation of the switch.

My invention, therefore, includes the novel elements and the combinations and arrangements thereof described below and illustrated in the accompanying drawings, in 35 which—

Fig. 1 is a side elevation of my switch, partially in section, and in which certain portions are broken away to show the interior construction;

40 Fig. 2 is a rear elevation showing the container and operating handle in two positions;

Fig. 3 is a fragmentary detailed view 45 showing one method of attaching the closing element to the switch box;

Fig. 4 is a section of the cover for the terminal box;

50 Fig. 5 is a section of Fig. 1 in the plane 5—5;

Fig. 6 is a fragmentary section of Fig. 5 in the plane 6—6;

Fig. 7 is a rear elevation of the circuit making and breaking element showing the inertia operated actuating element in two 55 positions;

Fig. 8 is a perspective view of the cam and stop plate with a fragmentary showing of the elements coacting therewith; and

Fig. 9 is a section of Fig. 1 in the plane 60 9—9.

Referring to the drawings, 1 represents a hermetically sealed container within which the circuit making and breaking mechanism is placed. In Fig. 1 the front 65 of this container is shown open but it is intended in all cases that the container will be hermetically sealed as is shown in Fig. 3. Here, a suitable cover plate, 2, is secured to the container, 1, by means of screws, 3, 70 and a gas proof gasket, 4, is interposed between the cover plate and the container. Secured in the rear central portion of the container, 1, is a hollow stub shaft, 5. Loosely fitted upon the shaft, 5, so that it 75 may turn freely thereon, is a collar, 6, which is rigidly connected to operating lever, 7, provided with handle, 8. There is also loosely fitted upon the stub shaft, 5, so that it may turn freely relative thereto, a 80 cam and stop plate, 9, provided with a central, hollow boss or hub, 10, which is exteriorly threaded at 11, to receive the nut, 12. Fitted over the boss, 10, is the wall plate, 13, provided with suitable openings, 85 14 and 15, for the reception of screws for securing the plate to the wall or outlet box. Next to the plate, 13, there is fitted over the boss, 10, a fiber disk, 16, provided with the peripheral flange, 17. The cam plate, 9, the wall plate, 13, and the fiber disk, 16, are secured together in fixed relation by means of the nut, 12, and these elements together with the operating handle, 8, are held in assembled position upon the stub shaft, as 90 95 shown in Fig. 1, by means of the threaded collar, 18, which is secured in place by means of the set screw, 19.

Surrounding the collar, 6, is the helical spring, 20, (see Figs. 1 and 5), the end por- 100

tions of which, 21 and 22, depend somewhat fixed position but the container may be below the axis of the stub shaft, 6, and turned on the stub shaft relative thereto. In operative position the handle, 8, will normally be either in the position, 8, or the 70 position, 8', as shown in Fig. 2, and the container will also be tilted as shown at 1, or at 1', in Fig. 2. When the container and the plate, 13, are in either of the positions shown in Fig. 2, it is to be understood that the cam follower is either in the recess, 34, or in the recess, 35. In either position the operating handle, the container, and the end portions of the spring, 20, are in the relative 75 position shown by the solid lines in Fig. 5. As the operating handle is moved toward the position, 8'', shown in Fig. 5, the end portion, 22, of spring, 20, will be held against the projection, 23, on container, 1, but the end portion, 21, of spring, 20, will be moved to the position, 21' by the coaction 80 therewith of the projection, 24, on the lever, which moves to the position, 24'. This movement stresses the spring, 20, and develops therein a certain potential force 85 which causes the end portion, 22, of the spring to press strongly against the projection, 23, on the container. The only thing which prevents the container from tilting as 90 the handle, 8, is turned is the resistance offered to the cam follower in raising itself 95 out of the depression, 34, or the depression, 35. The further the operating handle, 8, is moved from the position shown in the solid lines the greater the potential energy 100 developed in the spring and finally when the energy, so developed, is sufficient to cause the roller, 30, to compress the spring, 33, and ride up out of the depression onto the flat portion, 36, of the cam, this energy is 105 transmitted to the container and it tilts abruptly and continues to turn until it is stopped abruptly by the coaction of the stop, 26, with the projections, 28 or 29. It will 110 be apparent that when the container has stopped after this operation it may be abruptly tilted back to the original position and the movement abruptly stopped in that position by simply moving the operating handle in the opposite direction.

40 Referring particularly to Fig. 8 it will be apparent that the cam element is provided with two depressed portions, 34 and 35. Intermediate these depressed portions is a flat portion, 36, which merges smoothly but 45 rather abruptly into the depressed portions, 34 and 35, at either end. Since the stop element, 26, and the cam follower, 27, are 180 degrees apart, it is to be understood that the portions, 28 and 35, and the portions, 50 29 and 34, respectively, of the cam plate are approximately 180 degrees apart. That is, when the cam follower is in depression, 34, stop, 26, abuts against projection, 29, and similarly, when the cam follower is in 55 depression, 35, the stop, 26, abuts against the projection, 28.

Before describing the circuit making and breaking mechanism it may be well to describe the operation of the foregoing mechanism. It is to be understood that the device is secured to a wall or outlet box, 37, by screwing the plate, 13, thereto. The rear view of the device when so secured would be as shown in Fig. 2. That is the plate, 60 13, and the cam and stop plate, 9, are held in

I utilize the foregoing apparatus to effect 115 the making or breaking of an electrical circuit by the means hereinafter described. Referring now more particularly to Figs. 1, 7 and 9, 38 represents generally a push button switch of the well known type ordinarily 120 used on a wall for turning on or off the electric lights in the room. It is provided with two push buttons, 39 and 40. The interior construction of a switch of this character is so well understood in the art 125 that only a brief description thereof is thought necessary.

Fig. 9 illustrates the operation of the switch in more or less diagrammatic way. The push buttons are connected together by 130

the bell cranks, 41 and 42, which are pivoted at 43. In the position of the parts shown in Fig. 9 with button, 40, depressed, the circuit from contact, 44, to contact, 45, 5 is broken, but when button, 39, is depressed a connection is made between contacts, 44 and 45, by means of the movable elements, 46 and 47.

In order to effect the actuation of these 10 push buttons within the sealed container and without any direct contact therewith from the exterior, I provide an inertia actuated element of sufficient mass to effect a depression of the buttons. The operation of 15 this element may be understood from the following description.

The principal mass in the inertia actuated element is the arcuate mass of metal, 48, 20 which is pivotally mounted to oscillate over the push buttons. The push button switch is secured to a suitable frame, 49, by the usual lugs, 50 and 51, in the same way that a similar wall switch is secured to its face 25 plate (see Fig. 7). This frame is provided with upstanding portions, 52 and 53, on either side of the plane passing through the axis of the push buttons. Centrally secured to the mass, 48, by any suitable means 30 is an inverted U-shaped element represented generally by the numeral, 54, the depending portions of which, 55 and 56, extend radially from the arcuate mass, 48, and are rotatably mounted on a pin, 57, passing through the upstanding portions, 52 and 53, 35 of the frame. That is, the mass, 48, may oscillate about the pin, 57, to the position, 48', shown in Fig. 7.

Within the U-shaped element and secured to the mass, 48, by means of the screw, 58, 40 and the helical compression spring, 59, is the element, 60, having depending portions, 61 and 62, in contact with the top of the push buttons, 40 and 39, respectively. The element, 60, is also provided with depending portions, 63 and 64, adjacent the elements, 56 and 55, respectively, and which are provided with slotted openings, such as shown at 65 in Fig. 9, and which embrace pin, 57. From the foregoing it will be apparent that as the mass, 48, is oscillated about the pin, 57, as an axis the buttons, 39 and 40, will be alternately depressed and raised so that the circuit will be alternately made and broken.

55 The switch mechanism may, of course, be secured within the container in any suitable way although it is desirable that the pin, 57, about which the mass, 48, oscillates be substantially coaxial with the stub shaft,

60 5. In Fig. 7 I have shown the frame, 49, provided with struck in portions, 66 and 67, coacting with the portions, 68 and 69, of element, 70, secured to the inside bottom of the container. Where these coacting elements 65 are so designed as to fit rather closely and

provided they are somewhat resilient, the switch mechanism with the oscillating mass assembled thereon may be slid into the container from the rear and be held therein quite rigidly.

70 It is perfectly obvious that the switch mechanism which is employed may be adapted to connect or break a plurality of electrical circuits as well as a single circuit. In the device illustrated I have shown two 75 circuits evidenced by the fact that four wires are shown, in Figs. 1 and 2, extending from the switch mechanism through the hollow shaft to the exterior of the receptacle. After these wires are in place the hollow 80 shaft is hermetically sealed by wax, 71, in which the wires are embedded. In order that connections may be readily made from the switch I have provided the periphery, 17, of the fiber disk, 16, with binding posts, 72, 73, 74 and 75. While it is not necessary, 85 it is at least desirable that those portions of the wires which extend from the hollow shaft to the binding posts be covered and I have therefore provided the fiber cap, 77, 90 shown in Fig. 4, which may be secured to the fiber disk by means of the screws, 78.

95 In operation my switch is secured in the wall, 37, or to an outlet box by means of screws passing through plate, 13, and when so secured, the parts are either in the relative position indicated by the solid or dotted lines in Fig. 2. In either one of these positions the relative positions of the mass, 48, and the switch mechanism are as shown in 100 Fig. 7. That is, one of the push buttons is elevated and the other push button is fully depressed so that the circuit is either made or broken. Assuming the mass and the switch mechanism to be in the relative position shown by the solid lines in Fig. 7 and the circuit broken, the circuit may be made by suddenly tilting the container, as described above, by means of the operating handle, 8. Inasmuch as the mass and the 105 switch mechanism are connected through and movable with the container, and the mass, 48, is adapted to oscillate about the axis, 57, which is coaxial with the axis about which the container is tilted, it will be apparent that after the assembly shown in Fig. 7 is abruptly rotated about the axis, 57, and the rotating movement is abruptly stopped, the inertia of the mass, 48, will cause it to continue to move in the direction of the 110 arrow, 76, to the position, 48', thus button, 39, will be depressed and button, 40, raised so that an electrical circuit will be completed through the switch.

115 It will be quite apparent from the foregoing that the circuit making and breaking mechanism is entirely enclosed in the container, 1. The hollow shaft, 5, is hermetically sealed with wax or other suitable material, and the opening in the back of the 120

container is sealed by the cover plate, 2, and gasket, 4. Hence, the container is fluid proof so that any arcs which may occur as the circuit is broken cannot possibly come 5 in contact with any inflammable or explosive gases about the exterior of the switch. If desired, a small opening, sealed with a pipe plug, 80, may be provided in the top of the container so that a non-viscous insulating oil may be introduced therethrough to 10 fill the container. In such a case, any oil on the outside of the container will be a positive visible indication that the container leaks so that oil may be added to keep it full, 15 or the leak repaired.

In the drawings, I have illustrated only a 20 so called push button switch which is actuated by two exposed buttons. It will be apparent however that a switch of the well known toggle type having substantially the same internal construction as a push button switch but actuated by a single exposed element may be employed. In such a case the 25 mass, 48, obviously may be fixed directly to the exposed operating element.

It is therefore to be understood that the drawings are merely illustrative, that the words which I have used are words of description rather than of limitation, and that 30 changes within the purview of the appended claims may be made without departing from the true scope and spirit of my invention in its broadest aspects.

What I claim is—

35 1. In a switch of the character described, the combination with a sealed container, of means therein for making or breaking an electrical circuit, a mass mounted to oscillate in said container for actuating the circuit making or breaking means, a pivotal mounting for said container, and means exterior of said container for imparting a sudden movement thereto to effect an oscillation of said mass.

45 2. In a switch of the character described, the combination with a sealed container, of means therein for making or breaking an electrical circuit, a pivotal mounting for said container, a mass mounted to oscillate in said container about an axis below its center of gravity and coacting with the circuit making and breaking means to effect an actuation thereof, and means exterior of the 50 container for imparting a sudden movement thereto to effect an oscillation of said mass.

55 3. In a switch of the character described, the combination with a sealed container, of means therein for making and breaking an electrical circuit, a mass mounted to oscillate in said container for actuating the circuit making and breaking means, a pivotal mounting for said container, and means exterior of said container for abruptly starting 60 and stopping a movement thereof about its

pivotal mounting to effect an oscillation of said mass.

4. In a device of the character described, the combination with a tiltable sealed container, of means therein for making or 70 breaking an electrical circuit, inertia operated means within said container actuated by the tilting thereof to effect an actuation of the first mentioned means, and means 75 yieldingly associated with said container for suddenly tilting the same.

5. In a device of the character described, the combination with a tiltably mounted, sealed container, of means therein for making or breaking an electrical circuit, inertia 80 operated means therein actuated by tilting the container for effecting an actuation of the first mentioned means, means exterior of the container for tilting the same, and means for abruptly stopping the tilting movement. 85

6. In a device of the character described, the combination with a tiltably mounted, sealed container, of inertia operated means 90 therein actuated by tilting the container for making or breaking an electrical circuit, yielding means for temporarily restraining the tilting movement of said container, and means exterior of the container for developing a tilting force sufficient to release said 95 container and to effect the tilting thereof.

7. In a device of the character described, the combination with a sealed container having inertia operated means therein actuated by tilting the container for making or breaking an electrical circuit, a pivotal mounting 100 for said container, means for positively limiting the range of movement of said container thereon, yielding means for temporarily restraining the tilting movement of said container, and means exterior of the 105 container for developing a tilting force sufficient to release said container and to effect the tilting thereof.

8. In a device of the character described, a support, a sealed container movably 110 mounted on said support and enclosing a switch provided with separate elements for effecting an actuation thereof to make or break an electrical circuit, and oscillating means operable by a bodily movement of 115 the container and coacting with said elements to effect an actuating movement thereof.

9. In a device of the character described, a support, a sealed container movably 120 mounted on said support and enclosing means for making and breaking an electrical circuit, and an oscillating element operable by a bodily movement of the container and coacting with said means to effect an actuation thereof. 125

10. In a device of the character described, a support, a sealed container movably mounted on said support and enclosing a switch provided with separate elements for 130

effecting an actuation thereof to make or break the circuit, and an oscillating element operable by a bodily movement of the container and coacting alternately with said 5 separate elements to effect an actuation of said switch.

11. In a switch of the character described, the combination with a support, a sealed container movably mounted on said support 10 and enclosing means for making or breaking an electrical circuit and a movable mass for effecting an actuation of the first mentioned means, of means for imparting a bodily movement to the container to effect 15 a switch actuating movement of said mass.

12. In a switch of the character described, the combination with a support, a sealed container movably mounted on said support and enclosing means for making or breaking 20 ing an electrical circuit and a movable mass for effecting an actuation of said first mentioned means, of a mounting for said container, and means for imparting a sudden but limited bodily movement to said container 25 to effect a switch actuating movement of said mass by the inertia thereof.

13. In a switch of the character described, the combination with a fluid-tight container, of means therein for making or breaking 30 an electrical circuit, movable means exterior of the container for building up potential energy, and means for transforming said energy into kinetic energy and transmitting it by a bodily movement of said 35 container to said first mentioned means to effect an actuation thereof.

14. In a switch of the character described, a support, a sealed container movably mounted therein, a mass movable relatively 40 to said container mounted therein, an electric switch mounted within said container and actuated by said mass, means exterior of the container for building up potential energy, and means for utilizing the potential 45 energy so built up for moving said container and thereby actuating said switch by the kinetic energy of said mass.

FRANCIS R. MEGINNISS.
